Primary Examiner — Mojtaba Tehrani*(74) Attorney, Agent, or Firm* — Ferguson Case Orr Paterson(57) **CLAIM**

The ornamental design for a pelletizing machine, as shown and described.

DESCRIPTION

1. Pelletizing machine

1.1 : is a perspective view of the design;

1.2 : is a left view thereof;

1.3 : is a front view thereof;

1.4 : is a right view thereof;

1.5 : is a rear view thereof;

1.6 : is a top view thereof;

1.7 : is a bottom view thereof.

The broken lines in the reproductions depict unclaimed portions of the pelletizing machine only and form no part of the claimed design.

1 Claim, 7 Drawing Sheets(56)
